UNITED STATES PATENT OFFICE.

WAYNE D. WAMSLEY, OF CHESTER, PENNSYLVANIA, ASSIGNOR TO THE LESTER PIANO COMPANY, OF PHILADELPHIA, PENNSYLVANIA, A CORPORATION OF PENNSYLVANIA.

PLAYER-PIANO.

1,177,071.

Specification of Letters Patent.

Patented Mar. 28, 1916.

Application filed September 16, 1914. Serial No. 861,992.

To all whom it may concern:

Be it known that I, WAYNE D. WAMSLEY, a citizen of the United States, residing at Chester, Delaware county, Pennsylvania, have invented certain Improvements in Player-Pianos, of which the following is a specification.

This invention is designed to provide inter-connected mechanism for operating in sequence the pedal mechanism of a player piano and the shutter for concealing it, the apparatus being so arranged that the operator can conveniently control the aforesaid devices while remaining in the natural sitting position for playing the instrument.

The characteristic features of my invention are more clearly set out in the following specification and the accompanying drawings in illustration thereof.

20 In the drawings, Figure 1 is a front elevation of the lower part of a player piano illustrating the application of my improvements thereto; Fig. 2 is an enlarged transverse sectional view on the line 2—2 of Fig. 1; Fig. 3 is a rear elevation of the bottom panel of the piano showing the position of the apparatus when the shutter is closed; Fig. 4 is a similar view showing the position of the apparatus when the shutter 30 is open; and Fig. 5 is a top plan view of the structure shown in Fig. 4.

In the drawings is shown the lower part of a usual player piano comprising the casing 1, the removable lower front panel 2 containing the pedal opening 3, and the bellows 4 fixed to the casing and having pivoted thereto the frame 5 on which are pivoted the pedals 6 for operating the bellows through the links 7 and 8. A track or way 9 fixed on the panel 2 supports, through the hangers 10, the sliding shutter 11 for closing the opening 3 when the pedals are folded up out of operative position. A bent lever 12, fulcrumed on the stud 13 on the panel 2, 45 has a head 14 containing a slot comprising the straight portion 14' and the curved portion 14'' and is pivotally connected with a link 15, the link being pivotally connected with the shutter 11 so that when the lever 50 is rocked on its fulcrum the shutter is moved along the track. A lever 16, fulcrumed on the stud 17 on the panel, has a head 18 containing a slot comprising a straight section 18' and a section 18'' curved oppositely to the slot section 14''. The lever 16 is pivot-

ally connected with the link 19 which is pivotally connected with the bearing 22 on the pedal frame so that when the lever 16 is rocked on its fulcrum the pedal frame is elevated and lowered. The connection between the link 19 and the bearing 22 is preferably made readily detachable to permit the convenient removal of the panel 2 from the piano. A crank shaft 23 is journaled in a bracket 23' fixed to the panel 2 intermediate of the fulcrums of the levers 11 and 16 and has a pin 24 engaged in the slots in the heads 14 and 18. The parts are so proportioned and disposed that the curved slot section 14'' is concentric with the axis of the shaft 23 during substantially the portion of the throw of the shaft when its pin 24 is in engagement with the edge of the slot section 18', and the curved slot section 18'' is concentric with the axis of the shaft 23 during substantially the portion of the throw of the shaft when its pin 24 is in engagement with the slot section 14'. The lever 16 is preferably a lever of the first class while the lever 12 is preferably a lever of the second class.

In operation, when it is desired to open the shutter and lower the pedals, the handle 20 of the shaft 23 is turned anti-clockwise from the position shown in Fig. 3 to the position shown in Figs. 1 and 4. In moving to this position, the pin 24 runs freely in the curved slot section 18'' until it comes to the section 18', but engages the side of the slot section 14' so as to rock the lever 12 on its fulcrum and draw back the shutter. As the pin rises it acts in the slot section 18' to rock the lever 16 and lower the pedal frame, which acts freely in the slot section 14'' now substantially concentric with the shaft 23. In the reverse operation, upon turning the handle of the shaft clockwise from the position shown in Fig. 1, the pin first travels freely through the slot section 14'', and engages the edge of the slot section 18' to elevate the pedals and, upon reaching the end of these slot sections, runs freely in the slot section 18'' and engages the edge of the slot section 14'' to close the shutter.

Having described my invention, I claim:

1. In apparatus of the character described, the combination of pedal mechanism and a shutter, with inter-connected mechanism for operating said shutter and pedal mechanism in sequence, said inter-connected mechanism having curved bear-

- ings movable into positions concentric with a common center, whereby said pedal mechanism and shutter each remains inoperative during a movement of the other.
5. 2. In apparatus of the character described, the combination of a shutter and pedal mechanism, with a lever connected with said shutter, a lever movable relatively to said pedal mechanism, and means comprising a pin connected with said levers for operating them in sequence.
3. In apparatus of the character described, the combination of pedal mechanism and a shutter therefor, with a lever connected with said shutter, a lever connected with said pedal mechanism and a shaft having a crank which is connected with said levers, said crank being movable relatively to and operating said levers.
20. 4. In apparatus of the character described, the combination of pedal mechanism and a shutter therefor, with a device for operating said pedal mechanism, a device for operating said shutter, a shaft, and means operated by said shaft for operating said devices, said devices each having a way for engaging said means, said devices respectively being movable to positions in which the respective ways are concentric with the axis of said draft for engaging said means.
25. 5. In apparatus of the character de-

scribed, the combination of pedal mechanism and a shutter therefor, with a lever connected with said pedal mechanism and 35 provided with a way having a curved section, a lever connected with said shutter and provided with a way having a curved section, and a pin movable in said ways for 40 rocking said levers.

6. In apparatus of the class described, a shaft movable about its axis, a pair of levers each having a way provided with a curved section concentric with the axis of 45 said shaft in positions of the respective levers, means for rocking said levers, and operating mechanism and a cover therefor operated by said levers.

7. In apparatus of the character described, a pair of levers each having a way 50 comprising a curved section, means for rocking said levers so as to bring said curved sections alternately into position concentric with a common center, and devices comprising a fulcrumed member and a slide operated by said levers.

In testimony whereof, I have hereunto set my name this 12 day of September, 1914, in the presence of the subscribing witnesses.

WAYNE D. WAMSLEY.
